UNITED STATES PATENT OFFICE.

GEORGE F. C. HOUGHTON, OF NEW YORK, N. Y., ASSIGNOR TO SYDNEY B. HOPKINS, OF SUMMIT, NEW JERSEY.

SOUND BOX.

Application filed February 24, 1922. Serial No. 538,901.

To all whom it may concern:

Be it known that I, GEORGE F. C. HOUGHTON, a citizen of the United States, residing at New York, in the county and State of New York, have made certain new and useful Improvements in Sound Boxes, of which the following is a specification.

The invention relates to novel and useful improvements in sound boxes of sound reproducing machines, and more particularly to the stylus bar mechanism.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part thereof, illustrate one embodiment of the invention, and together with the description, serve to explain the principles of the invention.

Of the drawings:—

Fig. 1 is an elevation of a sound box embodying the invention;

Fig. 2 is a fragmentary view, partly in section and partly in elevation, taken on line 2—2 of Fig. 3;

Fig. 3 is a fragmentary elevation, on an enlarged scale, looking at the lower part of Fig. 1 from the right; and

Fig. 4 is a similar view to Fig. 3, but showing a partially different bearing for the stylus bar.

In the reproduction of sound from records, the movement of the stylus bar is both very delicate, rapid and complex, owing to the minute, delicate, rapidly-succeeding and various changes in the sound groove of

the record, due to corresponding changes in the pitch, duration and timbre of the recorded sounds (the last being due to the number and nature of the overtones in the source of the sound). In order to communicate the

minute, delicate, complex and rapidly changing sound formations of the record accurately and adequately as vibrations to the sound box diaphragm an exceedingly fine, rigid, stable and yet free pivotal or axial

mounting for the stylus bar is required.

That is, the stylus bar must have freedom, accuracy and quickness of movement in order to receive from the record and to impart to the diaphragm the correct sound producing vibrations. The object of the present invention is to produce such a stylus bar mounting.

Referring now in detail to the accompanying drawings, illustrating by way of example the present preferred embodiment of the invention, the sound box 1 may be of any standard or suitable form, so far as concerns the principal features of the present invention, and will not be described in detail.

The sound box reproducing diaphragm 2 is mounted in the sound box in the usual or any suitable manner, and the stylus bar 4 is attached thereto at 3, likewise in any suitable and adequate manner.

The stylus bar 4, as embodied, has as integral or constituent parts thereof, the arm 5, which at its upper end is affixed to the diaphragm 2 and at its lower end is fixed to the outer end of an inwardly-extending bracket or arm 6. At its inner end the arm 6 joins the center of a horizontally disposed pivot bar 10, which will be later described.

From beneath or outside the center of pivot bar 10 the needle holding bar 7 extends and is provided at its outer end with a suitable clamping screw or other holding means 9 for a record needle 8.

The present invention is directed to the mounting of the stylus bar to effect or produce the results or objects already described. As preferably embodied, in the peripheral part of the sound box 1 are fixed two outwardly-projecting, pointed pins 12 and 13, the points thereof bearing in very shallow indentations in the face of the pivot bar 10, approximately near the respective ends thereof.

The points of these pins constitute or determine the pivotal points, or axial line, about which the stylus bar rocks. This constitutes a minimum of bearing surface, with the greatest fineness and accuracy of edge or point, but with great freedom of motion and consequent quickness of action, while the spaced apart position and the seating of the points preserves the necessary accuracy of movement and position, and also prevents undesirable and detrimental translational or angular movement.

Means are provided for firmly and accurately holding the pivot bar to its bearings or axial line while permitting the desired free, quick and accurate movement of the bar on the bearings. As embodied, two balls 14 and 15 are seated in the other face of the pivot bar and preferably directly opposite, respectively, the points 12 and 13, the balls being supported to hold the bar to the pins, while the balls are free to roll on their support with the movement of the stylus bar. The bearings are thus held firmly to position without restricting their freedom or quickness of action. Any other movement of the stylus bar is also prevented, which movements are the causes of "blasting" and other detrimental effects on the tone production.

Accordingly, the balls have spherically shaped seats (Fig. 2) in the face of the pivot bar 10, and the supports for the balls, respectively, are flat strips 18 and 19, curved in a radius about the bearing points of the pins 12 and 13. The balls are thus free to roll on their supports 18 and 19, while the supports acting through the balls press the bar firmly to its axial line, giving the desired live, free but always stable and accurate bearing.

The supports 18 and 19 are preferably flat springs, bent to fit into, and to be seated in, slots or kerfs formed in projecting flanges 20 and 21 formed on or fixed to the periphery of the sound box. These springs hold the balls 14 firmly against the bar 10, yet with a resilient action that keeps the pressure about constant and that automatically takes up any looseness that may occur. The ends of the strips are shown upset at 22 and 23 on the opposite sides of the respective flanges 20 and 21. The flange 21 is shown recessed at 27 to give clearance for the stylus bar.

As a convenience in assembling, longitudinally disposed grooves 24 and 25 are formed from the ball seats to the ends of the pivot bar 10, whereby the balls may be sprung into their seats.

In Fig. 4, knife edge pins 26 and 26' are shown in place of the pointed pins 12 and 13, but usually the pointed pins will be found preferable.

It will be understood that changes in the exact form of the mechanism as shown and described may be made, without departing from the principles of the invention and without sacrificing its chief advantage.

What I claim is:—

1. A sound box comprising a diaphragm supporting frame, a pivot bar for carrying a stylus, a flat U-shaped spring the ends of which pass through part of the diaphragm supporting frame and are secured thereto, and bearing elements on opposite sides of the pivot bar, the pivot bar and bearing elements being resiliently cradled in operative relation by means of the U-shaped spring.

2. A sound box comprising a diaphragm supporting frame, a laterally extending flange at one side of the frame, a pivot bar for carrying a stylus and provided with longitudinal grooves near each end thereof, bearing elements seated in the grooves, bearing elements on the other side of the pivot bar, and flat U-shaped springs for resiliently holding the several bearing elements and the pivot bar in operative relationship, the ends of the U-shaped spring passing through the flange of the diaphragm frame and being secured thereto by being bent over into contact therewith.

In testimony whereof, I have signed my name to this specification.

GEORGE F. C. HOUGHTON.
